UNITED STATES PATENT OFFICE

ERNEST C. PAGEL, OF CHICAGO, ILLINOIS, ASSIGNOR TO ELGIN BUTTER TUB COMPANY,
OF ELGIN, ILLINOIS, A CORPORATION OF ILLINOIS

FASTENER FOR TUB COVERS

Application filed February 6, 1929. Serial No. 337,907.

This invention relates to a fastening means for a receptacle cover, and while the invention is applicable to many covers for receptacles, it is particularly designed to hold a cover on a butter tub. A very successful and efficient cover for a tub or similar receptacle has recently been developed, which cover has a metallic flange depending about the top of the tub or receptacle. The fastener of the present invention is particularly adapted to be used with this cover.

It is an object of this invention, therefore, to provide a very simple and efficient form of fastener for holding a cover on a tub or other receptacle.

It is a further object of the invention to provide a fastener or holder for holding a cover on a tub or other receptacle, comprising a strip of material having means at one end adapted to be driven into the receptacle and having a substantially right angle bend adjacent its other end, the strip being bent into a curve or eye adjacent said right angle bend.

It is more specifically an object of the invention to provide a fastener or holder for holding a cover on a tub or receptacle which cover has a depending flange with a slot therethrough, said holder comprising a narrow strip of material having means at one end adapted to be driven into the side of the receptacle and having a substantially right angular bend adjacent its other end, the portion beyond said bend being inserted through said slot and being bent into an eyelet so as to be disposed adjacent the tub, said right angle bend extending under the edge of said flange and closely adjacent the tub.

These and other objects and advantages of the invention will be fully set forth in the following description made in connection with the accompanying drawings, in which like reference characters refer to similar parts throughout the several views, and in which:

Fig. 1 is a view in side elevation of the upper portion of a tub with the cover thereon showing the fastener applied thereto;

Fig. 2 is a vertical section taken on line 2-2 of Fig. 1 as indicated by the arrows;

Fig. 3 is a view in vertical section of the

tub and cover showing the application of the fastener thereto;

Fig. 4 is a perspective view of the fastener before being applied to the cover and tub;

Fig. 5 is a perspective view of a modified form of the fastener, and

Fig. 6 is a perspective view of still another modification of the fastener.

Referring to the drawings, a portion of the upper part of a receptacle 10 is shown and while the receptacle might be of various forms, in the embodiment of the invention illustrated it is shown as in the form of a wooden tub having a slight upward flare. The tub has a cover 11 thereon having a metallic binding 11a secured on its edge which binding has a depending flange 11b shown as flaring slightly downwardly and having a bead 11c at its lower edge. The flange 11b is provided with a plurality of slots, one of which 11d is shown. These slots are somewhat elongated and extend parallel to and adjacent the bead 11c. A hoop 10a is shown as extending about the tub 10. While the invention is applicable to various kinds of covers, the one shown has been found to be a very successful cover and is being commercially marketed.

The fastener of the invention comprises a strip of material 12, which strip is preferably made of metal such as iron and has prongs 12a formed at one end and bent substantially at a right angle thereto. It will be noted that the terminal prong 12a is made by cutting away a portion of the side of said strip, said portion being slightly tapered, while the inner prong 12a is somewhat shorter and made by punching out the prong from the side of the strip. Both prongs are sharpened at quite an angle, the incline being disposed oppositely on the respective prongs. The strip 12 adjacent its other end is bent outwardly as shown at 12b at a sharp angle and as illustrated, substantially at a right angle. The portion of strip 12 beyond the bend 12b is then reversely bent in a curve 12c which is shown as substantially semi-cylindrical. The terminal portion 12d then extends at a right angle to the main portion of

strip 12 and as illustrated in Fig. 4, the same extends substantially at a right angle to strip 12.

In applying the fastener to the cover 11, the cover is first placed in position on the tub 10 as shown in Figs. 1, 2 and 3. The terminal portion 12d is then placed downwardly through the slot 11d until the curved portion 12c rests on the bead 11c or on the bottom of slot 11d. The strip 12 is then swung inwardly toward the tub, the terminal portion 12d thus being further bent and brought into substantially parallel relation with the main portion 12 of the strip, a substantially complete cylindrical eyelet being formed at the curved portion 12c and said terminal portion 12d being disposed between the tub and the main portion of strip 12. The prongs 12a are then driven into the side of the tub and the fastener occupies the position shown in Fig. 2. It will be noted that the terminal portion 12d is at the inner side of the fastener and there are thus no ends, points or terminal portions exposed. The cover is securely held in position on the tub. When the cover is to be removed the prongs 12a can be easily pried out with a screw-driver or other thin implement and the fastener can remain on the cover. The cover can be again placed on the tube and the fasteners again used for securing the same. The prongs 12a will of course preferably be driven into another place in the tub than that which they originally occupied.

35 In Fig. 5 a different form of fastener is shown comprising a strip 13 having prongs 13a at one end similar to the prongs 12a on the strip 12. The upper end of strip 13 is bent outwardly into a partially cylindrical form as shown at 13b. This fastener will be applied to the tub by looping the portion 13b through the slot 11d and then driving the portion 13 into the side of the tub. If desired, the portion 13b may be more completely closed after being engaged with the cover.

In Fig. 6 another modification is shown in which a strip 14 is used, the same having holes adjacent one end to receive the lugs of a staple 15. Strip 14 has a bend 14a intermediate its ends, the portion 14b beyond the bend 14a then being bent into a curve to extend substantially parallel to the portion of the strip adjacent the staple 15. The strip of fastener 14 will be applied in the same manner as the fastener 12. The portion 14b will be inserted downwardly through the slot 11d until the portion adjacent the bend 14a rests on the bead 11c or the bottom of the slot 11d. The strip 14 is then swung toward the tub thus bending terminal portion 14b until it comes into position substantially parallel to the portion 14 and disposed between the same and the side of the tub. Staple 15 is then driven into the side of the tub. When completed the fastener 14 will appear very much as the fas-

tener 12 except that the portion 14b is longer. The strip 14 is usually made of thinner metal than the strip 12.

From the above description it is seen that applicant has provided an easily applied, simple and efficient fastener for a receptacle cover. The fastener may be easily and quickly made and at small expense. The same is easily applied and acts to secure the cover in place very firmly. The fastener remains on the cover and as above stated, can be repeatedly used. Also as set forth above, there are no projecting ends on which the clothing or hands of the operator may be injured. The slight taper on the terminal prong 12a and the shorter inner prong permit ease of driving of the prongs and prevents spreading of the prongs before the driving is completed. It will be noted that the angle which the prongs 12a make with the main body portion 12 of the fastener, as clearly shown in Figs. 2 and 3, is somewhat less than a right angle. The prongs are so bent so that they will more easily drive into the side of the tub. If the prongs were exactly right angular or any greater than right angular there would be a tendency to widen the angle as the prongs were driven into the tub. It is the intention to make the prongs so that they start somewhat upwardly into the side of the tub along the general line of an arc drawn with its center at the center of the eyelet at the top of the fastener. This makes it much easier to drive the prongs without the same bending.

The device has been amply demonstrated in actual practice and found to be very successful and efficient. The same has been enthusiastically endorsed by butter dealers and is being commercially manufactured.

It will, of course, be understood that various changes may be made in the form, details, proportions and arrangement of the parts, without departing from the scope of applicant's invention, which, generally stated, consists in a device capable of carrying out the objects above set forth, in the novel parts and combinations of parts disclosed and defined in the appended claims.

What is claimed is:

1. A combination with a container cover having a rim at its edge disposed adjacent the side of said container and having a slot therethrough, of a fastener comprising a strip having one end extending downwardly through said slot, said strip being bent downwardly to form an eyelet embracing the portion of said rim below said slot, said strip being bent substantially at a right angle at the lower outer side of said eyelet so as to extend downwardly along the side of said container and having means at its lower end adapted to be driven into the side of said container and withdrawable therefrom.

2. A combination with a container cover having a rim at its edge disposed adjacent the

side of said container and having a slot there-through, of a fastener comprising a strip having an upper portion extending downwardly through said slot to extend along the side of said container, said strip being then bent downwardly and forming an eyelet extending over and around the portion of said rim below said slot, said strip having a substantially right angle bend therein at the lower side of said eyelet and below said rim, the portion below said bend extending downwardly alongside of the container and overlying said upper portion and having sharpened means at its lower end driven into the side of said container and withdrawable therefrom.

In testimony whereof I affix my signature.
ERNEST C. PAGEL.
